UNITED STATES PATENT OFFICE

110,020

DESIGN FOR A COMBINED TABLE AND RADIO RECEIVING SET

Daniel J. Crowley, Grosse Pointe, Mich.

Application April 4, 1938, Serial No. 76,285

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Combined Table and Radio Receiving Set, of which the following is a specification, reference being had therein to the accompanying drawing, forming a part thereof, wherein; my new design for a combined table and radio receiving set is illustrated by a perspective view.

In my design of combined table and radio re-

ceiving set, the rear side of the table top differs from the front side shown in the drawing in that the depressed portion having the indicating dial therein is omitted and the adjacent side walls of the table top are identical.

The dominant feature of my design consists in the portions illustrated in full lines. The member shown in dotted lines represents a tray.

I claim:

The ornamental design for a combined table and radio receiving set substantially as shown and described.

DANIEL J. CROWLEY.
